UNITED STATES PATENT OFFICE.

JAMES T. COWLEY, OF NEW YORK, N. Y., ASSIGNOR TO THE LAMSON CONSOLIDATED STORE SERVICE COMPANY, OF NEW JERSEY.

STORE-SERVICE APPARATUS.

SPECIFICATION forming part of Letters Patent No. 402,567, dated May 7, 1889.

Application filed August 25, 1885. Serial No. 175,309. (No model.)

To all whom it may concern:

Be it known that I, JAMES T. COWLEY, of New York, in the county of New York and State of New York, have invented certain new and useful Improvements in Store-Service Systems; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to store-service apparatus for stores, warehouses, and the like, and has for its object to convey cash and parcels from one place to another, or from the salesman's counter to the cashier's desk, and vice versa, by which much valuable time is saved as compared with the old methods.

The present invention is durable in its construction, partly automatic in its operation, and easily manipulated.

To these ends the invention consists of improvements in the receiver and restorer and means for avoiding the shock or thud of the car when it reaches its terminal ends, by which means the car is gradually received and lowered for either loading or unloading, so that when the car reaches its terminal end it is caught by the receiver, which yields to the weight of the car, and which unwinds a spring whose resiliency is predetermined to correspond to the weight and permits the car to easily and gradually drop to its normal position at either the salesman's or cashier's end. Said spring or weight is also designed to take up the slack and automatically wind up the cord when the carrier is restored to the way.

It further consists in means for raising the movable end of the track to its working position before the car is started on its journey over the track or way, which is in this instance a weight, volute spring, or other spring mechanism, all of which will be more fully herein-after described.

In the drawings, Figure 1 represents a side elevation of a wire-way apparatus, broken away in the middle. Fig. 2 is a sectional view of a spring wound within a flanged wheel,

which form I prefer to use; Fig. 3, a top plan view of a double bifurcated or forked arm through which the operating-cord works. Fig. 4 shows a modification of my receiver and restorer with a single spring. Fig. 5 is another modification of my receiver and restorer, showing a weight instead of a spring, and it is evident that many modifications may be made without departing from the spirit of my invention. Fig. 6 is an enlarged view of a portion of Fig. 1, illustrating the operation of the forked arm and the cords with respect thereto.

Referring to the drawings, A represents the cashier's desk; B, the wrapper's counter; C, the sales-station, and D the wire way.

E represents the rope upon which the car F and contents are received and lowered to the counter. At the sales-station is placed an upright rod or pipe, a, from which the wire D is drawn, and upon which the carriage f is moved up and down. This carriage f, supporting one end of the way or track, consists of a yoke or bracket enveloping the rod a and provided with anti-friction rollers for bearing upon said rod as it is moved up and down to raise and lower the way. Upon the rod a, at or near the top, is placed a spring-roller, b, upon which is wound a cord, o, the opposite end of the latter being fastened to the carriage f, as represented. To the lower part of the carriage f is also attached a cord, h, which passes through a forked or bifurcated arm placed at or near the lower end of the rod or pipe a, and upon which cord is placed at proper distances stops to regulate the grade or inclination of the track.

One end of a rope, E, is attached to a spring-roller, g, or it may be to a weight, W, as in Fig. 5, which is so adjusted as to prevent the car from lowering without the assistance of a salesman, and to also take up the slack of the rope used in lowering the car to the proper distance below the track when the car is raised. In operating the apparatus the salesman first places the goods or cash in the receptacle, then releases the cord h from the forked arm m, when the cord o will be wound upon the spring-roller b, thus at the same time raising the end of the track to the proper elevation. The slack in the rope E, caused

by thus raising the wire way or track, will of course be taken up by the spring-roller *g*, and this will result whether the way be raised when the car is in the position shown in Figs. 1 and 4, or whether the car be first elevated to the way ready to travel thereover to its other end when the way is raised or properly inclined. The salesman then, by pulling down on the rope *E*, elevates the car and contents to the track *D*, the spring-roller *g* assisting and also taking up the slack of the rope, which otherwise would lie upon the floor.

Another way of elevating the track would be to have the forked arm *m* pivoted at *n*, Fig. 6, to the side of the rod or pipe *a*, and having a button, *y*, placed on the rope *E*, so positioned with respect to the forked arm that when the slack in the rope *E* is taken up by the spring-drum *g* in the act of elevating the car to the track the said button *y* will contact with the arm *m* at one side of its pivot and tilt it downward, as shown in dotted lines, Fig. 6. This tilting of the arm *m* will raise its opposite end, so as to permit the cord *h* to slip out of the fork at that end, its button *i* sliding outwardly against the under side of the arm until it reaches an opening large enough to permit it to pass, thus allowing the track to be elevated through the tension of the spring in the winding-drum *b*.

The cord *h* has three buttons or stops, *l*, *i*, and *j*, upon it, the middle one, *i*, being the smallest. The button *l* by contact with the arm *m* limits the downward pull upon the cord *h*, and thus determines the lower position of the track and prevents it from being pulled down too far. The smaller button, *i*, as before stated, contacts with the under side of the arm *m*, and when the latter is in its horizontal or normal position will prevent the track being raised, and will be released therefrom and permit the track to be elevated when the arm *m* is tilted or when it is positively freed from engagement therewith, and the button *j* limits the upward movement of the track. After the carriage is elevated the rope or cord *E* is pulled down, which raises the car to the track and gives to it an impetus to travel on its way to the other end, where it is secured. The roller-spring *g* in the meantime takes up the slack rope *E*.

There is a like spring-roller at the cashier's end for like purpose.

Having thus described my invention, what I claim, and desire to secure by Letters Patent, is—

1. In an apparatus for store-service, a receiver and restorer, one end of said restorer having a spring take-up mechanism for raising the car to the track, in combination with a spring elevating device for raising the sliding end of the track, as set forth.

2. The combination, with the track of a store-service apparatus, of a yoke or bracket provided with anti-friction rollers, a pivoted arm, *m*, and a graduated rope or cord for raising and lowering said yoke and contacting with said arm, as set forth.

3. The combination, with a store-service apparatus provided with a receiver and restorer and a cord for raising and lowering the same, of the forked arm *m* and a pulley with the spring-roller mechanism, as set forth.

4. In a store-service apparatus, the combination of the car, the track, a cord upon which the car is received and lowered at the end of the track, a spring mechanism which takes up the slack of said cord when the car is placed on the track, another cord and spring mechanism which automatically elevates the end of the track, and buttons for holding the last said cord and spring mechanism from moving, substantially as described.

5. In a store-service apparatus, the combination, with the car and the track, of a rope upon which the car is received and lowered, a cord by which one end of the track is raised, a button on said cord, and a pivoted forked arm, with which said button engages, adapted to be tripped by the rope on which the car is received to permit the last said cord and spring mechanism to operate, substantially as described.

In testimony that I claim the foregoing as my own I affix my signature in presence of two witnesses.

JAS. T. COWLEY.
